LEE W. BOLLOW, OF CHICAGO, ILLINOIS.

Fixture for Water-Closet Bowls.

1,426,950.

Specification of Letters Patent. Patented Aug. 22, 1922.

Application filed April 22, 1920. Serial No. 375,695.

To all whom it may concern:

Be it known that I, LEE W. BOLLOW, a citizen of the United States, residing at Chicago, county of Cook, State of Illinois, have invented a certain new and useful Improvement in Fixtures for Water-Closet Bowls, and declare the following to be a full, clear, and exact description of the same, such as will enable others skilled in the art 10 to which it pertains to make and use the same, reference being had to the accompanying drawings, which form a part of this specification,

Often, when the outlet from the modern 15 water closet bowl becomes choked, it is necessary completely to detach the bowl from its support so as to permit access to the obstructed zone from the under side; the reason for this being that the circuitous discharge passage from the bowl prevents a rod 20 from being pushed through the same from one end to the other.

The object of the present invention is to provide means whereby an obstruction may 25 be quickly and conveniently removed from the circuitous discharge passage of a water closet bowl, without detaching or lifting the bowl.

In carrying out my invention I make a 30 hole in the rear wall of the bowl opposite the juncture of that part of the passage extending upwardly and rearwardly from the bottom of the bowl with that part of the passage extending downwardly at the rear of 35 the bowl and provide a simple and novel closure for the hole which will make a permanently watertight joint and at the same time give ready access to the outlet passage so as to permit a rod to be pushed forwardly 40 if there is an obstruction in the upper or lateral branch of the passage, or downwardly if there be an obstruction in the upright section of the passage.

Difficulty is experienced in making a 45 satisfactory connection between the water inlet through the so-called "spud" and the vitreous part of the bowl. The same means for securing a watertight joint at the clean-out hole may be employed for attaching the 50 spud in place and therefore, viewed in one of its aspects, my invention may be said to have for its object to produce a simple and

novel construction and arrangement for effecting a permanent watertight joint between a fitting and the vitreous wall of a 55 water closet bowl or the like.

The various features of novelty whereby my invention is characterized will herein-after be pointed out with particularity in the claims; but, for a full understanding of 60 my invention and of its objects and advantages, reference may be had to the following detailed description taken in connection with the accompanying drawing, where- 65 in:

Figure 1 is a top plan view of the vitreous portion of a bowl adapted to be equipped in accordance with the present invention;

Fig. 2 is a section taken approximately on line 2-2 of Fig. 1; 70

Fig. 3 is a rear elevation of the bowl;

Fig. 4 is an axial section on a larger scale than Figs. 1 to 3, through the clean-out opening and closure, only a fragment of the 75 vitreous wall being shown;

Fig. 5 is a section taken approximately on line 5-5 of Fig. 4, the vitreous wall and the valve being omitted;

Fig. 6 is an end view, on a reduced scale, 80 of the locking washer;

Fig. 7 is a vertical central section through the spud and the means for fastening it to the bowl; and

Fig. 8 is a central axial section taken at 85 right angles to the plane of Fig. 7.

Referring to the drawing, 1 represents a water closet bowl of any usual or suitable construction having the usual syphoning outlet passage formed of an inlet section, 2, and an outlet section, 3. In the rear wall of 90 the bowl, just opposite the rear end of the section 2 and the upper end of the section 3 of the outlet passage is a hole, 4. This hole is preferably round except that it is provided with diametrically-opposed sections, 5, 95 of larger radius than the body portion of the hole. Extending through this hole is a cylindrical sleeve, 6, having on the inner end two flange sections, 7, of such size and shape that when the sleeve is placed opposite the hole 4 with the flange members registering with the wings, 5, of the opening in the bowl, the flange members may be passed through the wall of the bowl from the ex- 100

terior to the interior. Then, upon turning the sleeve through an angle of ninety degrees, the flanges are brought behind the solid sections of the wall lying between the 5 wings 5, thus preventing the sleeve from being withdrawn in the outward direction.

For the purpose of locking the sleeve against rotation, I provide a locking washer, 8, having an internal diameter such that it 10 may be slipped over the projecting end of the sleeve on the outer side of the bowl and provided with long arc-shaped lugs, 9, shaped to fit into the wings, 5, of the opening in the bowl and long enough to project 15 between the flange sections, 7, on the sleeve. It will be seen that the washer is prevented from turning by reason of the fact that its lugs are seated in the wing portions of the hole in the bowl; its lugs in turn serving as 20 stops for the flange sections on the sleeve and preventing the sleeve from turning. After the sleeve and locking washer have been placed in position, a compressible gasket, 10, is placed over the washer, this gasket 25 preferably being larger in external diameter than the washer and being thickened in that area which projects beyond the washer, so as to engage the outer wall of the bowl and form a complete covering for the flange portion of the washer. A nut, 11, is 30 then screwed upon the projecting end of the sleeve, compressing the gasket and forming a watertight joint which need not be disturbed after the parts have once been assembled. At its inner end the sleeve 6 is 35 provided with an inwardly-projecting annular flange, 12, having an outwardly-facing seat, 13. Co-operating with this valve seat is a valve, 14, the stem of which is preferably 40 screwed into a plate, 15, as indicated at 16, which serves as a cover plate for the nut 11 and to which it is fastened by means of studs, 17, or other suitable means. The screw threaded connection between the stopper 45 and the plate permits the stopper to be adjusted relatively to the supporting plate. When access to the interior of the outlet passage in the bowl is desired, the plate, 15, is 50 unscrewed, the stopper coming away with the plate.

The same expedient that I have adopted for locking the sleeve in the clean-out opening may be employed to advantage for securing a watertight joint between the spud and the top wall of the bowl. I have therefore provided the bowl with a water inlet opening, 18, which is preferably of the same size and shape as the hole 4 with its wings 5 so as to make the fittings interchangeable. 55 The spud, 19, like the sleeve, 6, has flange sections, 20, similar to the flange sections 7. The same locking washer, 8, with its locking lugs, 9, fits into the opening 18 and co-operates with the flanges, 20, of the spud to prevent 60 rotation of the spud. Over the washer

is placed a gasket, 10, like the one heretofore described, and the parts are locked together by means of a suitable nut, 21, screw threaded on the spud. If desired, a thin washer, 22, may be placed between the nut 70 and the gasket for the purpose of taking the wear induced by the rotating nut when the latter is tightened.

While I have illustrated and described with particularity only a single preferred 75 form of my invention, I do not desire to be limited to the exact structural details thus illustrated and described; but intend to cover all forms and arrangements which come within the terms employed in the definitions of my invention constituting the appended claims.

I claim:

1. A water closet bowl having a hole in a wall thereof to give access to the interior 85 through said wall, a sleeve fixed in said hole, said sleeve having at its inner end an outwardly-facing seat, a closure for the outer end of said sleeve, means for detachably securing said closure in place, and a stopper supported by said closure and engaging said seat.

2. A water closet bowl having a hole in a wall thereof to give access to the interior through said wall, a sleeve fixed in said hole, 95 said sleeve having at its inner end an outwardly-facing seat, a closure for the outer end of said sleeve, means for detachably securing said closure in place, and a stopper supported by said closure and engaging said seat, said stopper being adjustable from and toward said seat.

3. A water closet bowl having a hole in a wall thereof to give access to the interior through said wall, a sleeve fixed in said hole, 105 said sleeve having at its inner end an outwardly-facing valve seat, a ring-like nut on the outer end of said sleeve, a cover extending across the outer end of said sleeve, studs extending through said cover and into said 110 nut, and a stopper supported by said cover and engaging said seat.

4. A water closet bowl having a hole in a wall thereof, said hole comprising a round body portion having a plurality of wings, a 115 sleeve extending through said hole and having flange sections on the inner end capable of passing through said wings, said flange sections engaging the inner side of the said rear wall beside said wings, a washer surrounding the sleeve and having lugs extending through said wings and between said flange sections, a nut on the sleeve for clamping said wall between said flange sections and said washer, and a detachable closure 120 for the outer end of said sleeve.

5. A bowl having in a wall thereof a non-circular hole, a sleeve having at one end separated lateral flange sections adapted to pass through said hole in one angular position 130

of the sleeve and to engage with the inner side of the wall in another angular position of the sleeve, a washer surrounding the sleeve on the outer side of the wall, said washer having lugs fitting into said hole beside the sleeve so as to be held against rotation therein, said lugs extending inwardly between said flange sections and serving as stops to hold the sleeve against rotation, and a nut on said sleeve clamping said wall between said flange section and said washer. 10

In testimony whereof, I sign this specification.

LEE W. BOLLOW.
